United States Patent

Des. 237,963

Patented Dec. 9, 1975

237,963

ROOT CELLAR

Lynn C. Broadbent, Box 267, Alpine, Utah 84033, and
William B. Thomas, 8335 South 10th East, Sandy, Utah
84070

Filed Mar. 4, 1974, Ser. No. 447,579

Term of patent 14 years

Int. Cl. D25—99

U.S. Cl. D13—1 R

FIG. 1

FIG. 2

FIG. 3

FIG. 4

FIG. 5

FIG. 1 is a perspective view showing a root cellar incorporating our new design, taken from above and at one front corner of the root cellar;

FIG. 2 is a top plan view;

FIG. 3 is a front elevation view;

FIG. 4 is a side elevation view, the opposite side being a mirror thereof; and

FIG. 5 is a bottom plan view.

We claim:

The ornamental design for a root cellar, as shown and described.
